HEAT DISTRIBUTING UNIT

Lester L. Zeller, New Madison, and Ruben E. Zeller, Versailles, Ohio

Application December 1, 1938, Serial No. 243,342

1 Claim. (Cl. 237—63)

Our heat distributing unit is primarily intended to be used in connection with incubating cabinets and the like where it is necessary that extremely even temperatures be maintained.

We are aware that other means of heating, such as electric heating units, and the circulation of hot water in the conventional manner, have been used for the above-mentioned purpose, but the efficiency of the same have either been unsatisfactory, or the cost of heating therewith has been exorbitant.

It is, therefore, our principal object to provide a heat circulating unit which is compact, which is low in the cost of manufacture and maintenance, and which is adaptable for use with all of the different types of incubating cabinets.

Another object of the invention is the provision of a heat circulating unit which has the heating apparatus thereof heavily insulated and with means being provided therein for obstructing the flow of air therethrough when the circulating means thereof is idle.

Another object of the invention is the provision of a means positioned in the water circulating system thereof which automatically obstructs the flow of the water therethrough except when the circulating means is in operation.

A further object of the invention is the provision of a means for directing the flow of heated air from the unit in any desired direction.

Other objects and advantages of the invention will suggest themselves in the course of the following description, and that which is new will be defined and pointed out in the appended claim.

It is to be understood that the heat circulating unit, as shown and described, is a portable self-contained unit which is adapted to be connected to a hot water boiler, and which utilizes the heat from the water thereof.

It is also to be understood that the several members of the unit are old in other connections, but, when assembled in the unit, produce new and efficient results by providing an efficient means of distributing heat, and with the heat distributing portions being insulated against the undue escape of heat, resulting in an efficient unit with positive and automatic means for producing or obstructing the flow of air therefrom.

The most practical and satisfactory manner of carrying out the principles of the invention in a highly efficient and satisfactory manner is shown in the accompanying three sheets of drawings, in which:

Figure 1 is a front elevational view of the unit

cabinet with the directional vanes thereof being shown in closed position.

Figure 2 is a front elevational view similar to Figure 1, but with the cover thereof being removed, and with the directional vanes being shown partially open and adjusted to a different position from that shown in Figure 1.

Figure 3 is a rear end elevation of the unit cabinet showing the automatic swingable louvres which permit air to be drawn into the cabinet, and with the water conduits also being shown.

Figure 4 is a top plan view of the unit taken from line 4—4 of Figure 2.

Figure 5 is a detail vertical section through the rear end of the unit case taken on line 5—5 of Figure 4 and showing the rear set of automatic swingable louvres in detail.

Figure 6 is a detail right side elevation of the case, taken from line 6—6 of Figure 1, and showing the conduits extending therefrom.

Figure 7 is a detail sectional view, taken on line 7—7 of Figure 4, showing a front elevation of the forwardly positioned automatic swingable louvres.

Figure 8 is a detail section through the case taken on line 8—8 of Figure 4.

Figure 9 is a detail vertical section through the forward end portion of the case taken on line 9—9 of Figure 1, and showing the directional vanes in partial open position.

Figure 10 is a longitudinal section through the case taken on line 10—10 of Figure 2, and showing the relationship of the various members within the case.

Like parts are designated by like characters throughout the several views.

Referring now to the drawings in detail, 1 designates the case member which is comprised of the bottom member, two side members, and two end members. An aperture is formed through one of the side members for the reception of the electric wires 26.

40 The rear end member has two apertures formed therethrough providing for the reception of the inlet conduit 33 and the outlet conduit 21. A third and comparatively larger aperture is also formed through the rear end member to provide for the passage of air into the case. The forward end member of the case has an aperture formed therethrough, and into which the frame 3, of the directional vanes 5, is inserted.

45 2 designates the cover member with the downwardly extending flanges 21 being formed therearound, and which extend downwardly around

50

the upper edges of the side and the end members of the case.

3 designates the circular frame to which the directional vanes 5 are pivotally secured. The edge 3' of the frame 3 provides a flange by which the frame is secured in the forward end member of the case 1 by means of the clip members 7. The flange 3' is adapted to turn freely in the space formed between the clip members 7 and the inner face of the forward end of the case. A projecting knob 4 is rigidly secured to the frame 3 and provides for manual manipulation of the frame in a circular motion.

Each end of each of the vane members 5 has an ear portion 5' formed thereon, with the ear portions being turned at substantially right angles to the vane members. The ear portions 5' are pivotally secured through the circular frame member 3 by means of the rivets 8, or by other suitable means. Each of the vanes 5 has a knob member 6 secured thereto which provides for manual adjustment of each individual vane.

A box 9 forming a tunnel is secured to the rear face of the front end of the case by means of the flanges 9', with the tunnel extending rearwardly from the front end of the case. An aperture 10 is formed through the rear end of the tunnel, providing for the passage of air therethrough. Swingable louvres 11 are pivotally mounted in the tunnel adjacent the rear end thereof and are secured therein by means of the rods 12, the ends of which extend through the side members of the tunnel 9. The swingable louvres 11 normally hang downwardly from their respective rods 12, but assume the positions as shown by the broken lines in Figure 9 when air is forced thereagainst by means of the fan.

A radiator, comprised of the upper and lower pans 13 and 14 respectively, the fins 15, and the tubes 16, is positioned directly rearwardly of the tunnel 9. The radiator may be of the conventional type, with the tubes 16 providing for the circulation of water therethrough.

A wall member 17, having an aperture formed by the flange 17', extends entirely across the case and forms a compartment around the tunnel and the radiator. The space in the compartment is filled with the insulating material 41 which prevents heat from escaping from the radiator and the tunnel except through the tunnel in the manner intended.

An inlet tube 18 and an outlet tube 19 extend rearwardly from the upper pan 13 of the radiator, and to which the inlet conduits 20 and 21 respectively are secured by means of clamp members 22.

An electric motor 23 is provided within the case, and is supported by means of the bracket members 24. A fan member 25 is secured on the forward end of the motor shaft, with the fan being positioned adjacent the rear face of the radiator, and being partially enclosed by the flange member 17'. Electric current is conducted to the motor 23 through the wires 26. A pulley 27 is secured on the rear end of the motor shaft to provide power to the impeller pump 28 through the pulley 29 by means of the belt 30. The impeller pump 28 is supported from the motor 23 by means of the bracket members 31 and the cap screws 32.

One end of the conduit 20 is secured to the outlet tube of the impeller pump 28 by means of a clamp member 22. A conduit 33 leads from the hot water pipe 34 to the inlet tube of the impeller pump 28, and is secured at each end thereof by means of a clamp member 22.

The outwardly extending end of the outlet conduit 21 is secured to a short length of pipe 38 by means of a clamp member 22, with the opposite end of the pipe being threaded into one end of the check valve 39, and with the check valve being connected to the return line of the hot water boiler by means of the pipe 40. The check valve 39 prevents back pressure from forcing water into the radiator through the conduit 21.

A frame 37 is secured to the forward face of the rear end member of the case by means of the flanges 37'. Automatic swingable louvres 35 are positioned within the frame 34 by means of the rod members 36, as shown in Figure 5. The swingable louvres 35 normally hang downwardly from their respective rods 36, and assume the positions as shown by the broken lines only when the fan 25 is running and causing air to be pulled through the aperture which is normally covered by the swingable louvres 35.

In actual use, the wires 26 are connected in series with a thermostatic switch which is closed and opened by the variation in the temperature of the air surrounding the same. When the heat distributing unit is used in connection with an incubating cabinet, the thermostatic switch is located within the incubating cabinet. The pipe 34 is connected directly to a hot water boiler, and the pipe 40 is connected into the return line to the boiler. Also, the entire unit, including the case 1 and the cover member 2 may be insulated to prevent an undue escape of heat therefrom.

When the thermostatic switch is closed, the electric motor operates both the fan 25 and the impeller pump 28. Water is drawn from the hot water boiler through the pipe 34 and the conduit 33, and forced through the conduit 20 into the radiator by the impeller pump 28. The hot water is forced through the radiator and then through the outlet conduit 21, and through the check valve 39 and the pipe 40, and into the return line.

When the fan 25 is operated by the motor 23, the same draws air into the case through the aperture formed in the rear end of the case. The incoming air causes the swingable louvres 35 to swing to the open position as shown by the broken lines in Figure 5. The fan 25 forces air through the radiator and the force of the air causes the swingable louvres 11 to open, as shown by the broken lines in Figure 9, and with the air being directed as desired by means of the directional vanes 5. The volume of air passing through the case and the radiator is determined by the setting of the vanes 5.

When the thermostatic switch opens, the same allows the motor to stop rotating. As the motor stops, the fan and the impeller pump likewise stop. As the fan stops, the air ceases to flow through the case, and the swingable louvres 11 and 35 are closed by gravity, thereby sealing the ends of the case and preventing heat from escaping therefrom.

As the impeller pump stops, the check valve 39 closes against any back pressure which might develop.

It will be readily appreciated from the foregoing that, when the motor is stopped, the air is automatically kept from passing through the case and the radiator by reason of the swingable louvres being automatically closed by the cessation in the flow of air. It will also be seen that,

as soon as the impeller pump ceases to force water through the radiator and the conduit 21, the check valve prevents a flow of water through the radiator.

With the above-described arrangement, it is possible to maintain temperatures to within a fraction of a degree within an incubating cabinet. Also, the time required for the "heating-up" process (when the incubator is first started) is only a fraction of the length of time required by the use of electric heating units, or by the conventional hot water systems, thereby creating a saving in time and expense.

It is also anticipated that the unit may be operated in connection with a steam plant. In this event, the check valve and the impeller pump may be dispensed with. A solenoid-operated valve (operated by means of a thermostatic switch) may be inserted in the conduit 33, and the outlet pipe 19 rearranged and placed at the lowermost portion of the lower pan 14 to provide drainage of condensation from the radiator.

We desire that it be understood that we are not to be limited to the use of the invention in connection with incubating cabinets only, but the same may be used with equal efficiency and low cost in large rooms and the like.

We also desire that it be understood that minor changes may be made in the several parts and in the details herein shown and described, insofar as the changes may fall within the scope of the appended claim.

Having now fully shown and described the invention, what we claim, and desire to secure by Letters Patent of the United States, is:

10 A heat circulating unit comprising in combination, a case with a motor mounted therein, an impeller pump operated by said motor with a circulating fan being secured on one end of the motor shaft, a conduit carrying heated water to the intake opening of the impeller pump, a 15 radiator positioned within the case and connected to the outlet opening of the impeller pump by means of a second conduit, a third conduit carrying water from the radiator to a return line, a check valve connected with the third conduit preventing the flow of water in a reverse direction therethrough with the check valve forming a means whereby the radiator is maintained in filled condition.
